UNITED STATES PATENT OFFICE.

CARL F. KRESS, JR., OF JOHNSTOWN, PENNSYLVANIA, ASSIGNOR TO THE JOHNSON COMPANY, OF PENNSYLVANIA.

RAILWAY-SWITCH.

SPECIFICATION forming part of Letters Patent No. 633,723, dated September 26, 1899.

Application filed May 18, 1899. Serial No. 717,304. (No model.)

To all whom it may concern:

Be it known that I, CARL F. KRESS, Jr., of Johnstown, in the county of Cambria and State of Pennsylvania, have invented a new and useful Improvement in Railway-Switches, of which the following is a full, clear, and exact description, reference being had to the accompanying drawings, which form a part of this specification.

10 My invention relates to railway-switches of that type in which there is a tongue or point having a depending pintle at its heel end by which the tongue is swiveled to the foundation structure.

15 The object of my invention is to improve the durability and reliability of such switches by preventing a large part of the wear at the heel end of the tongue and thereby preventing any danger of "kicking" of the tongue, 20 which sometimes occurs when the parts at the heel end of the tongue have become loose. This sometimes shifts the tongue after the front wheels have passed onto the right track, so that the front and rear wheels may be 25 switched to different tracks, derailment almost necessarily occurring. I attain the objects which I have just set forth by seating the heel end of the tongue in a recess, one wall of which takes the place of a cut-away 30 portion of the tongue at its heel end, said wall being in alinement with the guard side of the tongue. I prefer also to have the opposite wall of the recess take the place of a cut-away portion of the tread side of the 35 tongue at its heel end, although instead of doing this I sometimes gain the same general object by carrying the wheel across the heel end of the tongue by a flangeway formed in the floor of the fixed portion of the structure.

40 I also prefer to provide a removable plate, (which may be made of unusually hard material,) which is secured to the switch structure and which has the recess and guard and tread portions herein referred to. These and 45 other portions of my invention will be more clearly understood by means of the following description.

Referring to the drawings, Figure 1 is a plan view of a portion of a switch constructed in accordance with my invention. Fig. 2 is a section of the same through the axial line of the pintle of the tongue. Fig. 3 is a similar view of a modified form of structure. Fig. 4

is a plan view of still another modification, and Fig. 5 is a section through the pintle of Fig. 4.

I have shown my improvements in connection with a switch having a foundation structure formed of a unitary steel casting, but it is of course obvious that this foundation structure may be a built-up structure or of some other specific construction than that shown. This foundation structure is represented by A.

A' is the tread-surface of the branching track formed as a part of the structure A.

A² is a guard portion of the structure, and forms the stop for the tongue when the latter is thrown over to shift the car to the branching track.

B is the tongue, having the tread side B' and the guard side B² at a little higher level. The point end of the tongue, and, in fact, of the whole switch, has not been shown because that is immaterial to my present invention, such portions of the structure being constructed in the ordinary manner well-known to those skilled in the art.

C is a hard plate—as, for instance, a plate of case-hardened steel—which is secured to the structure A at the heel end of the switch-tongue. I have shown this plate removably secured in place by wedges d and zinc d' in the manner which is now well known to the art, but which is set forth more fully in the patent to Moxham, No. 540,796. This plate, as clearly shown in the sectional views, has a recess which forms a seat for the heel end of the tongue B, a circular opening being formed through the floor of the plate through which the depending pintle B³ passes, the lower end of the pintle fitting in the passage a in the foundation structure A. By seating the tongue in the harder plate I prevent a large part of the wear which ordinarily comes from seating the tongue directly on the foundation structure, and I also provide a structure in which the seating-face is comparatively distant from the bearing between the pintle and the foundation structure.

From b, which is a point well in advance of the axial line of the pintle, to the extreme end of the tongue I cut away a portion of the guard-line of the tongue and in the place of this cut-away portion I provide an upwardly-extending portion c' of the wall of the recess

in the plate C. This wall c' therefore forms a continuation of the guard-line of the tongue. This fixed guard c' removes any danger of the flange of the wheel engaging the tongue 5 at its heel and shifting the tongue. This danger, though practically negligible when all parts are in good repair, arises frequently when the tongue becomes loose on its seat and in its bearings. The same danger is to 10 a less extent liable to arise by the weight of the wheel on the tread of the tongue at its heel end. This danger I prefer to remove by substantially the same means—that is, the opposite wall c² of the recess in the plate C 15 occupies the place of a cut-away portion of the tongue, so that the wall c² forms a portion of the tread-surface at the heel end of the tongue. The principal bearing of the ordinary wheel of commerce is close to the gage-line, and therefore the surfaces of the wall c² 20 will relieve the tongue at that point of substantially all weight.

So far the description which I have given has been directed to Figs. 1 and 2, which represents the form of construction which I prefer. In Fig. 3 I show a modification which only varies in that the plate is wider and has a tread-surface C², which takes the place of a short distance of the tread-surface A'. In 25 Figs. 4 and 5 I have shown this same tread-surface C², but I have shown another means for protecting the tread side of the tongue at its heel end. Instead of providing a tread-surface on the wall c², as in Figs. 1, 2, and 3, 30 I form a floor c³ on said wall, which is intended to carry the flanges of the wheels, as shown in Fig. 5, inclines c⁴ being provided at each end of the floor-surfaces c³. This I do not consider quite so good as the form shown 35 in the preceding figures, because the depth of the wheel-flanges are more or less irregular, and I prefer not to count upon employing the flanges for this purpose.

It will be seen that by this construction I 40 have greatly increased the reliability and durability of the switch without materially complicating the structure. By this construction also the whole of the top surface of the tongue is free and unobstructed, so that it is as 45 readily removable as in switches not embodying my improvements. At the same time I am also able to remove and renew the plate whenever desired.

I do not desire to limit myself to the specific details which I have shown and described, 50 for the three modifications of my invention merely illustrate three more or less preferred forms, and doubtless many other modifications may be made by those skilled in the art 55 without departing from the scope of the appended claims.

Having thus described my invention, what I claim, and desire to protect by Letters Patent, is—

60 65 1. In a railway-switch, the combination of a foundation structure, a plate having a recess and secured to said structure, a tongue

having a depending pintle at its heel end and seated at said end in the said recess, and an opening through the floor of said plate for the 70 pintle, substantially as described.

2. In a railway-switch, the combination of a foundation structure, a plate having a recess and secured to said structure, a tongue having a depending pintle at its heel end 75 and seated at said end in the said recess, an opening through the floor of said plate for the pintle, and a guard for one side of the heel end of the tongue formed by one wall of the recess, substantially as described. 80

3. In a railway-switch, the combination of a tongue having a depending pintle at its heel end, a member having a recess in which the heel end of the tongue is seated, and a portion of one wall of said recess taking the place 85 of a portion of the tread-surface of the tongue from the heel end of the tongue to a point in advance of the axial line of the pintle, substantially as described.

4. The combination, in a railway-switch, of 90 a switch-tongue having a depending pintle at its heel end, a recess in which said heel end is seated, the walls of said recess occupying cut-away portions of each side of the said tongue from the end thereof to points in advance of the axial line of the pintle, substantially as described. 95

5. The combination, in a railway-switch, of a foundation structure, a plate secured therein and having a recess, a pivoted switch-tongue 100 seated at its heel end in said recess, the walls of said recess taking the place of cut-away portions of the sides of the tongue, substantially as described.

6. The combination, in a railway-switch, of 105 a foundation structure having a recess, a plate removably secured in said recess and itself having a recess, and a switch-tongue seated in said last-mentioned recess at its heel end and having a depending pintle passing 110 through the floor of said plate, substantially as described.

7. The combination, in a railway-switch, of 115 a foundation structure, a plate secured to said structure, a switch-tongue seated at its heel end in said plate, an upward projection on said plate taking the place of a portion of the guard-line of the tongue at its heel end, and a second upward projection at the tread side of said tongue, substantially as described. 120

8. The combination, in a railway-switch, of a foundation structure, a plate secured to said structure, a switch-tongue seated at its heel end in said plate, upward projections on said plate at each side of said tongue, said projections taking the place of cut-away portions of the tread and guard-line of said tongue respectively, substantially as described. 125

In testimony whereof I have affixed my signature in presence of two witnesses.
